WALL MOUNTED HOLDER FOR A TUMBLER,
TOOTHBRUSHES, AND TOOTHPASTE

Eleanor M. Damiani, 525 Busti Ave., Buffalo, N.Y.

Filed July 8, 1960, Ser. No. 61,278

Term of patent 3½ years

(Cl. D4—3)

FIG. 1.

FIG. 2.

FIG. 3.

I claim:

The ornamental design for a wall mounted holder for a tumbler, toothbrushes, and toothpaste, as shown.
